Attorney*

UNITED STATES PATENT OFFICE.

VICTOR TOOTHAKER, OF EAST AURORA, NEW YORK.

DESIGN FOR A LAMP STAND.

Application filed January 25, 1923. Serial No. 4,993. Term of patent 7 years.

To all whom it may concern:

Be it known that I, VICTOR TOOTHAKER, a citizen of the United States, residing at East Aurora, in the county of Erie and State of New York, have invented a new, original, and ornamental Design for Lamp Stands, of which the following is a specification, reference being had to the accompanying drawings, forming a part thereof.

The figure is a perspective view of a lamp stand embodying the new design.

I claim:

The ornamental design for a lamp stand, as shown.

VICTOR TOOTHAKER.
